CHAIN FOR A BRACELET OR THE LIKE

Morris D. Gandelman, Fort Lee, N.J., assignor to Jacoby-Bender, Inc., Woodside, N.Y., a corporation of New York

Filed Mar. 14, 1968, Ser. No. 10,976

Term of patent 7 years

Int. Cl. D11—01

U.S. Cl. D45—4

FIG. 1

FIG. 2

FIG. 3

FIG. 1 is a top plan view of a chain for a bracelet showing my design;

FIG. 2 is a side elevational view thereof;

FIG. 3 is a bottom plan view thereof; and

FIG. 4 is an end elevational view thereof taken from the right hand end of FIG. 1.

The stippling on the drawing indicates contrast.

I claim:

The ornamental design for a chain for a bracelet or the like, as shown and described.
